UNITED STATES PATENT OFFICE.

JOHN GLENDENNING, OF NORWICH, ENGLAND.

SCHOOL-DESK.

SPECIFICATION forming part of Letters Patent No. 224,174, dated February 3, 1880.

Application filed September 10, 1879. Patented in England, January 4, 1879.

To all whom it may concern:

Be it known that I, JOHN GLENDENNING, of Norwich, England, have invented new and useful Improvements in and relating to School-Desks, of which the following is a specification, reference being had to the accompanying drawings.

My invention relates to school-desks; and my object is the manufacture of such desks with great economy, durability, and steadiness or rigidity, while increasing their convenience for the purposes of school-teaching under conditions highly favorable to the requirements of the pupils.

Referring to the accompanying drawings, Figure 1 represents a top view of a desk embracing my improvements; Fig. 2, a side view; Fig. 3, a front view of the desk part and its standard; Fig. 4, a side view of the desk part, showing the hinged part thereof folded over or closed; Fig. 5, a vertical section of the desk part on the line $x-x$ of Fig. 1, the hinged part being unfolded or turned down; Fig. 5^a, a similar section, showing another adjustment of the desk; and Fig. 6, a similar view to Fig. 1, showing a cheaper form of desk part, with a single casting of the two separate standards.

My improved desk is constructed with the desk proper, a , and the seat b , both supported immovably, with regard to each other, upon separate standards c c' , of a single casting, making a very cheap, rigid, and firm construction of school-desk. These standards are of unequal height to suit the desk and the seat parts, and they are connected by a base-ligature, c^2 , making the two parts one and bracing both against being thrown over, either forward or backward, said ligature being a single rib extending centrally in relation to the position of the pupil, and is therefore between the feet, and gives a free passage between the desk and the seat. The base part of each standard forms a saddle, c' , for a cross-sill, c^4 , which is secured thereto by screws, and need only extend out on each side of the ligature c^2 far enough to form lateral braces to prevent the desk from being turned over sidewise. The top of each standard is suitably widened by projections to allow the desk and seat parts to be properly secured thereon.

The desk part a forms a fixed box or receptacle

for books and other articles, and is provided with a hinged cover, a' , which may be turned back to open the box, as shown by dotted lines in Fig. 5, in which position it forms a rest for drawings or matter to be copied. When so used this cover is supported by a chain, a^* , secured to the under side of the cover and to the inner side of the box. The desk is also constructed with an adjustable part, a^2 , hinged at d , so that when turned down, as shown in Figs. 1, 2, and 5, it forms, in connection with the cover a' , an ample and conveniently-sloping surface for books and other articles used by the pupil. When this hinged part is turned up or closed, as shown in Fig. 4, it leaves space for the pupil to stand conveniently and comfortably between the desk and the seat. This part a^2 is open at its free side and forms a convenient receptacle for a slate or other article, which can be placed therein through its open side.

The fixed part a is provided with grooves e on its inner opposite sides to receive a ruler, which also serves to hold the books in convenient positions.

In Fig. 5^a I have shown the adjustable part a^2 turned up and supported by the cover a' , which is also raised in a vertical position, so that said adjustable part serves as a support for a book when the pupil is reading or learning from the same. For this purpose the hinged part a^2 is provided with a hook, a^3 , arranged to engage with a stud, a^4 , on the cover, as shown, so that when the two hinged parts are thus locked together they rest against and support each other. This hook is fitted in a recess at the side of the cover, so that when disengaged from the stud it can be turned back into the said recess and will not project beyond the edge of the part to which it is attached.

The seat-standard c' is formed with a back extension, c^5 , and constitutes, with the single-casting standards, a third part of the entirety.

The seat b is formed of pieces of wood b' b^2 , of suitable shape, and fastened both to the seat and to the back by screws.

The desk, although having the desk part and the seat part fixed immovably with regard to each other, is as a whole portable, and may be readily moved to any part of the school or taken out when required.

The desk shown in Fig. 6 differs from that shown in Fig. 1 in having its desk part of more simple and cheap construction, having no adjustable desk part or attachment. In this way 5 a combined desk and seat is formed in a very economical manner, having the required strength, rigidity, and adaptability for the purpose, a single casting comprising the desk-standard, the seat-standard, and the back of 10 the seat, all ready for the attachment of the necessary parts for use, and requiring no floor-fastenings, but having a bearing formed by the ligature and the cross-sills that gives a solidity of position to the desk and to the seat.

15 I claim—

1. In a school-desk in which the desk proper, *a*, and the seat *b* therefor are supported each by and upon separate single standards *c c'*, said standards, the seat-back *c'*, the base cross-saddles *c³*, and the base connecting part *c²*, which 20 together form a unitary casting, in combina-

tion with the cross-sills *c⁴* for said base-saddles of each single standard, substantially as and for the purpose herein set forth.

2. In a school-desk, the desk-box *a*, having 25 its cover *a'* hinged at or near the rear side at the top of said box, and the box part *a²* hinged at the front side of said box *a*, both said hinged parts being adapted to be raised in meeting positions over the desk-box, in combination 30 with means, substantially as described, whereby these hinged parts are locked together in such raised positions, substantially as and for the purpose herein set forth.

JOHN GLENDENNING.
